UNITED STATES PATENT OFFICE.

ROBERT T. WILLIAMS, OF QUINCY, ILLINOIS, ASSIGNOR TO H. M. SHEER COMPANY, OF QUINCY, ILLINOIS, A CORPORATION OF ILLINOIS.

STOVE HEAD.

Application filed August 17, 1927. Serial No. 213,622.

This invention relates to an improvement in stoves heads.

The object of the invention is to provide for the controlling of the draft in a stove 5 to adapt it to the burning of either hard or soft coal. Soft coal needs more draft than hard coal, and in order to allow for burning either, a direct smoke outlet is provided through the stove head for soft coal while 10 permitting of an indirect outlet to be provided for the burning of hard coal.

A damper is arranged in the stove head to cooperate with a permanent baffle plate fixed therein for regulating the draft through the 15 stove and the smoke outlet. This adjustable damper also permits of proper allowance being made instantly to off-set an unusually long or short length of smoke stack; or, in the case of a high wind, the closing of the 20 damper prevents the possibility of burning out a fire pot full of soft coal.

A fresh air inlet is provided in the stove head from one side of the smoke stack opening and a partition wall extends between 25 the fresh air opening and the smoke outlet so as to make it impossible for the air to pass directly to the smoke stack and to cause it to seek a path down into the head of the fire pot where it swirls around for a moment before 30 being sucked out on the smoke stack side of the partition. This partition wall also cooperates with the fixed baffle plate to keep the damper clean on both its top and bottom sides.

35 In the accompanying drawings:—

Fig. 1 is a perspective view of the head of a stove embodying the invention;

Fig. 2 is a disassembled perspective view thereof;

40 Fig. 3 is a top plan view of the baffle plate with the head removed, showing the damper in a closed position;

Fig. 4 is a similar view with the damper in an open position;

45 Fig. 5 is a transverse sectional view through the head of the stove; and

Fig. 6 is a similar view taken at right angles to Fig. 5.

This invention may be applied to a stove 50 of any desired construction, preferably of the coal-burning type, in which the usual damper is provided in the lower portion thereof for admitting air thereto to support combustion and the fire pot is designated

generally by the numeral 1. A cover 2 is secured over the top of the fire pot and is provided with an enlarged opening 3 in the top thereof, through which fuel may be introduced into the interior of the stove. A door 31 preferably closes this fuel opening 3 during the use of the stove. The cover 2 has downwardly extending flanges 4 therein, as shown in Fig. 6, and a permanent baffle plate 5 is secured within the cover 2 by means of bolts 6, which extend through the baffle plate 5 and the flanges 4. Spacers 7 may be used to suitably space the baffle plate at the desired height above the flanges 4. The baffle plate 5 is provided with a smoke opening 8 therethrough, as shown in Figs. 3, 4 and 5, which opening is adapted to be closed by a damper 9 pivoted as at 10 to the cover 2 and terminating in a control handle 11, which extends to the outer edge of the cover 2 and by means of which the damper 9 may be moved to open or close the smoke outlet 8 through the baffle plate. A stove head 12 is adapted to be secured upon the cover 2 of the stove, and extend over at least a portion of the area thereof, leaving the fuel opening 3 open, and this head may carry a suitable door to close the fuel opening if so desired.

In the top of the head 12 is arranged a fresh air opening 13 which may be closed by a damper 13' and at one side of said fresh air opening a smoke outlet 14 is provided, the latter being preferably spaced immediately above the opening 8 formed in the baffle plate 5, so as to allow the smoke to pass directly through the opening 8 to the smoke outlet 14 whenever the damper 9 uncovers the opening 8. A flange 15 extends across the head 12 between the fresh air opening 13 and the smoke outlet 14 and carries a partition wall 16, which is suspended therefrom and which separates the head 12 into air and smoke chambers 17 and 18, respectively. The wall 16 extends to a point in close proximity to the baffle plate 5 and is spaced only slightly thereabove to cooperate with said baffle plate for cleaning the damper 9 on both sides thereof, as it is shifted back and forth over the baffle plate. A flange 19 is formed on the front of the baffle plate 5 and overlies the front of the head 12, as shown in Figs. 1 and 5, and cooperates with the wall 16 for preventing the fresh air from passing directly to the smoke stack and forcing

it through an opening 20 in the front side of the chamber 17 into the upper portion of the fire pot, from where it may then be sucked out through a similar opening 21 in the front of the chamber 18 to the smoke outlet 14, or through the opening 8 thereto.

In the operation of the stove, the damper 9 may be properly regulated to burn either soft or hard coal. The damper is preferably closed to reduce the draft for burning hard coal but open to provide a direct draft to the smoke outlet 14, when soft coal is burned, this being regulated by the control handle 11. In burning hard coal, the draft will be indirect or over the edge of the baffle plate 5 through the opening 21 into the chamber 18, thence to the smoke outlet 14. The damper may also be regulated and properly adjusted to off-set an unusually long or short length 20 of smoke stack; or in the case of a high wind, the closing of the damper prevents a burning out of a fire pot full of soft coal.

When the damper (not shown), which is used to close the fresh air inlet 13 in the head 12, is open, fresh air is admitted into the chamber 17 from where it is forced to pass through the opening 20 over the edge of the baffle plate 5 into the top of the fire pot, after which it may be drawn out to the smoke outlet 14 either through the opening 21 or the smoke opening 8. This fresh air is prevented from passing directly from the fresh air inlet to the smoke outlet by use of the wall 16 and the flange 19.

In this way, the stove is adaptable for burning either soft or hard coal and an accurate control is maintained over the draft at all times. The construction is simple and easily controllable and effective for the advantages mentioned.

I claim:

1. The combination of a stove head having fresh air inlet and smoke outlet, a wall connected with the head and dividing it into air and smoke chambers, a baffle plate associated with the head and cooperating therewith to approximately close said chambers.

2. The combination of a stove head having fresh air inlet and smoke outlet, a wall connected with the head and dividing it into air and smoke chambers, a baffle plate associated with the head and cooperating therewith to approximately close said chambers, said baffle plate having a smoke opening therethrough and a damper for regulating said opening.

3. The combination of a stove fire pot, a cover connected therewith, a baffle plate fixed in the cover, a head mounted upon the cover and having fresh air inlet and smoke outlet, a wall connected with the head and dividing it into air and smoke chambers, communicating with the fire pot over the edge of the baffle plate, said baffle plate having a smoke opening therethrough communicat-

ing with the smoke chamber, and a damper for regulating said smoke opening.

4. The combination of a stove fire pot, a cover connected therewith, a permanent baffle fixed in the cover, a head mounted on the cover and having an air inlet and smoke outlet, a partition wall carried by the head and dividing it into air and smoke chambers, said head having openings in the front portions thereof for establishing communication between said chambers and the fire pot over the edge of the baffle, an upstanding flange carried by the baffle and cooperating with the wall for preventing substantial communication between the air and smoke chambers extended through the fire pot, said baffle having a smoke opening therethrough within the smoke chamber, and a damper for closing said smoke opening.

5. A stove of the character described including a head, a baffle plate carried thereby and having an upstanding flange, a top fitted over the head and having a depending flange for cooperating with the flange of the baffle plate to divide the top into smoke and air chambers, communicating with the interior of the stove over the edge of the baffle plate, and means for controlling the admission of air to the air chamber in the top.

6. A stove of the character described including a head, a baffle plate carried thereby and having an upstanding flange, a top fitted over the head and having a depending flange for cooperating with the flange of the baffle plate to divide the top into smoke and air chambers, communicating with the interior of the stove over the edge of the baffle plate, means for controlling the admission of air to the air chamber in the top, lugs formed in the head to hold the baffle plate in proper position, and a flange formed on the front edge of the baffle plate to limit the communication of the smoke chamber with approximately the center of the stove.

7. A stove head having a baffle plate extending thereacross in the lower portion thereof, and a partition extending between the baffle plate and upper portion of the stove head, and cooperating therewith to divide the stove head into separate chambers.

8. A stove head having a baffle plate extending transversely thereacross in the lower portion thereof, and a partition extending between the baffle plate and upper portion of the stove head and cooperating therewith to divide the stove head into air and smoke chambers, said stove head having communicating openings therebetween, over the edge of the baffle plate.

9. A stove head having a baffle plate extending transversely thereacross in the lower portion thereof, a partition extending be-

tween the baffle plate and upper portion of the stove head and cooperating therewith to divide the stove into air and smoke chambers, said stove head having openings in the front portion thereof approximately at the edge of the baffle plate for establishing communication between said air and smoke chambers and a stove body, and independent means connected with the baffle plate for establishing communication between the 10 stove body and smoke chamber.

In testimony whereof I affix my signature.

ROBERT T. WILLIAMS.
